UNITED STATES PATENT OFFICE.

SARAH WOOD CLARK, OF NEW YORK, N. Y.

PIANO-CASE.

1,121,166.

Specification of Letters Patent.

Patented Dec. 15, 1914.

Application filed April 14, 1914. Serial No. 831,709.

To all whom it may concern:

Be it known that I, SARAH WOOD CLARK, a citizen of the United States, and a resident of the borough of Manhattan, in the city, county, and State of New York, have invented certain new and useful Improvements in Piano-Cases, of which the following is a specification.

This invention relates to improvements 10 in piano cases, and it relates particularly to instruments equipped with my improvements in sounding boards in accordance with my Letters Patent of the United States, No. 763,157, dated June 21, 1904.

15 This invention consists in a sounding board supplemental to those shown in my said Letters Patent and serving to direct the musical sounds produced by the instrument.

20 In the drawing, 1, is a side view partly in section, of a piano case embodying my invention. This piano case is provided with a sounding board, 2, behind which is a sound chamber, 3, and behind this is an auxiliary 25 sounding board, 4, curved vertically.

The top of the case of this instrument is provided with a cover, 5, hinged at the rear. This cover is concaved beneath as shown at 6, to deflect the sound waves in a forward 30 direction when supported in the raised position shown in the drawing. It will be observed that upon being raised from a horizontal position to such raised position, this cover, 5, is carried somewhat to the rear 35 so that it no longer overhangs the front part of the instrument frame.

I have found that the volume of sound projected forwardly may be materially increased by extending this cover at its forward edge. Accordingly, I have supplied 40 this cover with an extension, 7, hinged or pivoted thereto, at 8, so as to be able to be supported in its raised position, in which position it forms a forward extension of the said cover, 5, and it may be dropped 45 into a vertical position when the cover is lowered so as to rest against or near the front of the piano case as shown in dotted lines in the drawing and forming an embellishment to the instrument case. 50

Having thus described my invention, I claim as new and desire to secure by Letters Patent:—

An upright piano or like instrument provided with main and supplemental sounding boards, and a casing provided with a cover hinged thereto, for deflecting the sound toward the front, said cover being furnished with a supplemental portion hinged along the front edge thereof and 55 when lowered extending down before the upright front portion of the casing. 60

Signed at Lakewood in the county of Ocean and State of New Jersey this 9th day of April A. D. 1914.

SARAH WOOD CLARK.
